N° 980.

*P. A. Palmers
Design for Plates of a Cooking Stove.*

Patented Jan'y. 12. 1858.

Fig. 1.

Fig. 2.

Dec. 980

Peter A. Palmer of Troy N.Y.
Letters Patent No. 980, Dated Jan. 12th 1858.

The schedule referred to in these Letters Patent and making part of the same.

To all whom it may concern:

Be it Known that I, Peter A. Palmer,

of the city of Troy, in the County of Rensselaer, and State of New York, have invented or produced a new and original Design, called the "Troy Capital", - for plates of a Cooking Stove; and I do hereby declare that the following is a full and exact description of the same, reference being had to the annexed photographic drawings making a part of this specification, in which,

Fig. 1 represents the front-plate, with its fire-door.²⁴

Fig. 2 a side-plate, with its feed and oven doors.

My design for the front-plate consists of the edge molding, a, the ornamental molding, b, and the enclosed swelling ground, c, of check-work; and that for each of the fire-doors consists of the central ornament, d, backed by the dotted check-work, e, and enclosed by the border molding, f. - My design for the side-plate consists of the panel formed by the molding, g, and ash-cup cap, h, as a border to the check-work, i, with the center ornament, j, - which panel forms the design of the feed-door of the fire box. - the funnel-shaped ash-cup, ornamented by the check-work, k, and acorn-drop, l, the moldings m, n, along the top and bottom, and the edge molding, n. - That for the oven-door consists of the large central ornament composed of the vase, o, grape-clusters, p, vines and leaves, q, and drapery, r, backed by the dotted check-work, s, and surrounded by the border molding, t.

What I claim as my invention or production and desire to secure by letters patent is the ornamental design and configuration of the several plates of a cooking stove herein described and fully ^{Exd} represented in the annexed photographic drawings. -
